METAL ROLLING MILL

James L. Adams, Jr., Youngstown, Ohio

Application June 7, 1933, Serial No. 674,661

27 Claims. (Cl. 80—31.1)

The present invention relates broadly to the art of rolling metals, and more particularly to the rolling of endless-belt type plates from ring ingots, whereby one mill, operating continuously at high speeds in one direction, after the insertion of each new ingot, or with an occasional reversal of direction if such should be preferred, can do the work now requiring a very considerable number of lower speed, more or less automatic, tandem-operated mills, to accomplish in the same period.

This leads to a very material simplification of total equipment required, with a far more than proportionate cut in total machinery cost, and in the total mill space requirements, for an equivalent output tonnage.

One of the prime objects of the present invention is to greatly cut the costs of rolling ultra long plates and strips, by increasing the output tonnage from a single mill, and at the same time greatly decrease the total number of mill stands required to carry out a given continuous rolling process, such as is required for really high tonnage outputs.

Another object of the present invention is to further cut plate and strip manufacturing costs, by the substantial elimination of all ingot-cropping and plate fish-tail end-scrap losses, concomitantly with the reduction of side-camber to an ultra low value, heretofore only attained commercially in the expensive tandem operated automatic mills, whereby the side-shear scrap losses reduce to a minimum.

An object of first importance is to provide a type of mill which may be operated at ultra high speed, as compared with usual mills, and with no time lost by reversals, or by the necessity of re-entering the plates in the rolls, or of transferring them from one set of rolls to another pair by some form of shifting mechanism.

Thus the total time taken for the job of rolling will be reduced to the ultimate minimum, increasing the daily output tonnage, and at the same time completing each plate or strip before it has cooled off so much as has been heretofore necessary in customary single-stand mills. This reduces materially the total work required of the mill, and increases the working life of its rolls.

An added object is to provide a mill which can be operated either as a continuous belt-mill taking ring-ingots and producing very long endless belt plates or strips, or as a regular two-high reversing mill producing flat plates or strips from hot slabs, or as a mill for first rolling rings which

are then cut and finished as flat plates or strips, all in the same machine, and with but a very brief stop for the cross-cutting operation, without removing the plate from the rolls to do so.

All this without changes in the mill structure, thus giving a job-mill of very general utility, and which in some cases can be readily made over from present mills.

An additional object is to provide a mill in which, by ultra-high operating speed, coupled with provision for inductive-electric, or for gas heating of the moving belt plate, the proper rolling temperature is maintained, thus permitting an entire rolling operation, from ring-ingot to moderately thin strip, to be carried out in one stage, without withdrawal from mill for re-heating purposes, and also permitting the rolling of certain alloy steels which require a very high rolling temperature to be maintained.

A further important object is to provide a high-speed and high-output mill, in which the roll set-up costs for every new job, and the roll maintenance costs during normal operation, will be far less than those required for any automatic multiple-stand tandem continuous mill, where many rolls must be kept up, and must be altered to suit any special pass shapes being rolled, and where also the very considerable number of rolls, housings, feed mechanisms, and gear-drives, vastly increase the normal chances of a breakdown occurring, as compared with my single-stand mill.

Another object is to furnish a means for delivering large endless belts or heavy rings of rolled steel direct from the mill, ready for forming large diameter tunnel linings, boilers, tanks, penstock sections, tubes, oil-cracking stills, and similar structures, with or without flanged edges, or connecting of sections.

Still another object is to provide a rolling process in which the hot metal is permitted the very ultimate minimum of contacts with cold rolls of mill and rough live-roll tables, thus not only materially aiding in holding up the temperature of plate, but greatly reducing the possibilities of hot-scoring of its smooth surfaces.

Yet another object is to permit the rolling of wide, thin sheets with a minimum of over-weight allowance, and of convexity, because of the higher general temperature of rolling maintained, and the possibility of very light loading of the rolls during the last two or three passes around the belt, so that little roll spring results.

An added object of the present invention is to provide means for spirally slitting an endless

belt of rolled plate, either into squares or oblongs, of an ultra long length in one continuous piece; or slitting into narrow bands, all before leaving the mill rolls, and all ready for immediate hot-rolling or drawing into rods.

Another object is to provide means for quickly cross-shearing a hot endless rolled belt, and running it out on the customary live-roll tables, and with zero end-scrap loss, giving also an ultra-long plate for welding later into pipe.

Such very long plates are very desirable for pipe welding, since the end-losses during the welding will reduce to a much smaller percentage of the total sheet weight than is usual for the customary shorter plates made by rolling flat slabs.

Another object is to produce plates and sheets substantially free from scale, due to the very small percentage of total elapsed time in which the plate is exposed to the open atmosphere, and away from the protecting pit of hot inert-gases provided.

Yet another object is to provide my mill with a separate scale pit, adapted to drain the scale from the main mill pit, and to take any broken belts which may happen to fall to the bottom of said main pit, and get them out of the way of further operations.

A very important object is to provide for the first time commercially adequate and rugged means for attaining all of the above objects in one practical mechanism.

My engineering designs indicate still other objects of importance to be attained, and such will appear to anyone skilled in the art to which my invention appertains.

With all the above and other objects in view, I have provided a practical means for accurately, expeditiously, and inexpensively rolling endless plate or sheet bands, or rings, of various thicknesses, widths, and formed-up contours, or flat, and in ultra long lengths, compared with present usual practices.

Since proper centrifugal casting, and subsequent "shaking", of a relatively wide and thin-walled ring-ingot, leads to the production of highly compacted, gas-free, and slagless metal, of more than usual uniformity of composition and texture throughout, and substantially free from all interior "pipes" and cavities, as indicated in my co-pending application, Serial #649,181, filed 12-28-1932, my present invention, which preferably utilizes such ingots, is capable of producing long belts, or flat plates and sheets of metal, which are very substantially free from all of the customary laminations, pockets, blisters, edge-cracks, and non-desired inclusions, now all too familiar to the mill man.

Since the usual continuous mills now known, contain many tandem stands of rolls, each of which must be very accurately driven at somewhat different sustained speed than those on either side thereof, by complicated and expensive electrical or other ultra-sensitive speed controls, these mills in the aggregate are very expensive pieces of apparatus, both to buy and to operate, whereas my present invention, which gives a similarly high tonnage output, from but a single stand of rolls, without any complicated inter-connected electrical speed-controls whatever, is vastly less expensive, with relatively very few parts, far lower roll set-up costs, much less chance of breakdown, lower renewal expense, and occupies far less mill space.

The single-stand mill also has the great ad-

vantage of far greater accessibility all around it, and since my mill preferably uses the ring-ingot, several times as much metal will be handled at one rolling, as in the flat-slab rolling machines, thus again economizing time, increasing output, and cutting manufacturing costs, and accentuating this still further by the total elimination of blooming-mill rolling costs.

In the accompanying drawings, I have shown, for purposes of illustration only, and not as determining the limits of my invention, a preferred form of mill, and two alternative forms of certain elements thereof, together with several closely associated appurtenances therefor, the complete assembly being adapted to facilitate the very rapid rolling of endless-belt plates or sheets, the rapid insertion into the mill of the ring-ingots required therefor, and the quick delivery of the completed product, either in the form of an endless-band, or cut and opened-up to form an ultralong flat plate, run out upon the customary live-roll tables of mill.

In the drawings, Figure 1 is a vertical cross-section of my mill, taken transverse to roll axis, on the lines I—I of Figures 2 and 4, respectively, in direction of the arrows, and indicating a preferred embodiment thereof.

Figure 2 is a vertical cross-section of mill proper, and of roll-removing carriage, but showing the rolls in elevation, the section being longitudinal to roll axis, and, with the exception noted, taken on line II—II of Figure 1, again looking in the direction of the arrows.

Figure 3 shows a transverse cross-section of the roll-removing carriage, and also indicates the top and withdrawn position of the plate-tightening drum or loose-pulley mechanism I have provided, the section being taken on the line III—III of Figure 2, looking in the direction of the arrows, and showing the clearance of said drum or pulley.

Figure 4 shows mostly in elevation, but partially in section, the two mill housings, with the moving elements of guillotine-shear, and the quickly withdrawable shuttle-type blade-bar therefor, indicated in position, as per line IV—IV of Figure 1, looking with the arrows, as before. I have here shown a piston-and-cylinder type of shuttle operating means, although a motor, reduction-gear and connecting-rod connection might equally as well be utilized, if preferred.

Figure 5 indicates another vertical cross-sectional view of my mill, taken on the line V—V of Figure 6, looking as indicated, and providing a similar, but more general view of my entire invention, than is given in Figure 1, since the later figure includes the pit structure under the mill proper, and the scale-pocket to the right thereof.

This figure also shows the belt-plate tightening pulley pretty well advanced on its trip down into the pit, as the rolling progresses, and about ready for its return trip up to just below, and off to one side of, the lower mill roll.

Figure 6 is another vertical cross-section, taken at right angles to Figure 5, as indicated by the line VI—VI and the arrows thereon. This view shows in a general way, the means provided for accurately guiding the plate-tightening pulley upward and then sharply to the right, as it is pushed up by the hydraulic plunger from below, and which is located in side wall of the pit.

Figure 7, similar to Figure 6, but taken on a much enlarged scale, shows to much better advantage the means provided to quickly raise.

lower, and to withdraw and return the plate-tightening pulley or drum, as the rolling of each new ingot gets under way. It also indicates the soft-copper rolls used to centrally position the 5 plunger of the very long hydraulic piston used, at spaced points along its travel, and further shows the vertical guide channel used to position the out-board end of pulley, and prevent its whipping in a horizontal plane passing in and out of the paper, as the rolling progresses. This 10 figure likewise shows the two guide channels extending off to the right, which are used in the withdrawal of the pulley from the line of the rolling, after the completion of one ring-belt plate, and before the new ingot can be inserted 15 for the next. Figure 7 is taken on line VII-VII of Figure 8, looking with arrows.

Figure 8 represents a horizontal section of certain elements of Figure 7, taken on the offset 20 line VIII-VIII thereof, again in the direction of the arrows. This Figure 8 shows to better advantage than the preceding, how the soft metal guide-rolls surrounding the hydraulic plunger, but fixed in space, allow the pulley-head mounting mechanism to pass therethrough without 25 blocking it at all, in the well provided for the hydraulic ram. Figures 8A and 8B are guide channel details per sections VIIIa and VIIIb of Figure 7.

Figures 9, 10, and 11, show two vertical sections transverse to each other, and a horizontal section, respectively, of the rough hot-gas-seal mechanism shown just below the slot leading to 30 plunger well in Figure 8, Figure 11 being simply 35 an enlargement of this detail in the figure just mentioned. At the top of Figure 9, I have shown how these loose leaves move over to one side to permit the pulley carrying plate to pass in either direction, but promptly return to sealing position thereafter. This is just to keep most of the 40 mill-pit heat out of the plunger well. The marked arrows in these three figures show the view directions.

Figure 12 is a vertical section taken similarly 45 to Figure 1, but indicating in addition the driving mechanism used for the pit-top seal gates, which are lowered whenever a new ingot is to be entered in the mill, and also showing how left hand gate is swung to the extreme left to permit removal on non-cut rings, if such happen to compose the order involved. I have also indicated 50 above, a right and a left hand automatic reversible motor-driven reeler, used to obtain further passes, made under tension after the cutting of the ring, if very thin sheets are required, 55 and below the mill frame I have shown the position of ingress and egress of an automatic slitter used to cut the endless-belt plate either into narrower continuous belts, or into an extremely long 60 spiral ribbon or square section.

Figure 13 is another vertical section, more or less similar to Figure 1, but showing as an alternative construction, a power-driven rotary type cross-shear, mounted to travel back and forth 65 across the belt-plate, at a point just below the main mill housing, and with any suitable form of plate-clamp run out just below the shear position, mounted upon a carriage similar to that of the rotary-shear.

Figures 14, 15, 16, and 17 show top or plan 70 view, end, and side elevations, and a vertical section taken on line XVII-XVII of Figure 16, respectively, of a preferred form of this rotary-shear mechanism, operable as a component part 75 of my mill structure, in such cases as involve

5 housings not readily adaptable to the guillotine type of shear first mentioned, as shown in Figure 1.

Thus in the case of a brand new mill design, 5 it can be readily adapted to the latter type of shear, but in changing-over an already built mill to conform to my invention, it may occasionally be necessary to use a shear of the rotary type.

Figure 16, in addition to the shear proper and 10 its traveling carriage, also indicates on the right, one form of propulsion for the latter, here a piston and cylinder, although a motor, large reduction gear, and a connecting-rod might be 15 preferred in some cases. A similar mounting and propelling means may be applied to the traveling 15 plate-clamp, Fig. 13.

Figures 18 and 19 indicate vertical and horizontal sections respectively, of a portion of one 20 mill housing, in which is mounted an adjustable ingot edge-guide roll, shown without sectionalizing, and positioned to right or left by the long screw functioning over a sliding key in the bushing shown in section to the right, by the gear 25 shown in section there. This limit-stop roll is shown in Figure 12 also, just to the right of, and above centre of, lower roll of mill.

Figures 20 and 21 illustrate by transverse and longitudinal sections respectively, a type of internally water-cooled non-puffing roll which I 30 prefer to use in connection with the mill of my invention.

Figures 22 and 23 show side and end elevations, respectively, and taken in the directions of the arrows, of an automatic ingot-carriage 35 adapted to run in under the right hand live-roll table of my mill, without disturbing the latter, and to lift up into place in line with the lower mill roll, a hot ring-ingot such as I use with my invention; or which carriage may be run in on a somewhat higher track as indicated on the 40 right in dotted outline, and deliver flat, hot slabs directly upon the right hand end of said live-roll table, in same Figure 22, without any alterations of structure being required in either case. But since this ingot-buggy has been made the 45 subject matter of my co-pending application, Serial #652,142, filed January 17th, 1933, it will not be elaborated upon further herein, being shown simply to complete the general picture of my mill, and indicate the latter's applicability 50 to the rolling of either ring-ingots or flat-slabs, or both, in any order of succession required.

Figure 24 gives in compact chart form, some operational data on my mill, but for one size of ingot only, so as to not make the presentation 55 too complex.

Figure 25 indicates in perspective elevation a 60 rolled plate belt which has been parted into narrow continuous bands, and Figure 26 a similar view of a rolled endless-belt which has been slit into an ultra-long continuous spiral ribbon, oblong, or square, as mentioned previously in connection with Figure 12.

Figure 27 shows a vertical section of the left-hand live-roll table of Figure 1, taken on the 65 line XXVII-XXVII thereon, and looking with the arrows. This table has to be of the lifting type, if endless bands or heavy rings are to be rolled in the mill, so as to provide means of egress therefor. The right-hand live-roll table, 70 however, as indicated in Figure 23, at top, may be stationary, and simply built of over-hanging type, to permit ingot carriage to run in thereunder from the front, or open side. In case a 75 reeler is required over the left-hand or swinging

live-roll table, as in Figure 12, this reeler will be on a long sliding-base, with motor to move it back away from plane of the drawings, whenever rings are to be rolled and removed as such, which will probably not be very often, since most of the belts will be cut open and run out as flats onto the top of this table, except in the case of very special orders.

In accordance with the present invention, and referring more particularly to Figure 1, there may be provided an apparatus including a spaced pair of roll housings 1, mounted upon the shoes 2, and carrying the power-driven mill rolls 3 and 4, of which the lower one 3 is removable endwise from the mill, while the upper roll 4 is mounted in roller bearings carried by the sliding chock 5, in turn depressed by the customary screw-down 6, operated by worm-wheel located within the gear-casing 7, meshing with a worm on shaft 8, actuated by a reversing motor, (not shown). Long tension-bolts 9 extend down behind the housing to bosses on side of chock 5, into which these bolts are screwed, after passing through the long compression springs 10, resting on pads on housing 1, and thus tending to lift the chock 5 and the upper roll, whenever screw 6 is backed up toward top of mill, as accords with usual practice. On the left I have shown a guillotine shear blade and mounting bar 11, operated by the eccentric-strap 12, carried by the roller-bearing 13, on eccentric 14, in turn mounted on shaft 15, carried by suitable brackets on the housing 1, and in its turn rotated by the large gear 16, driven by pinion 17, on shaft 18, carried by the bearing 19, on same housing, and all functioned by a motor of usual make, (not shown), with the customary contactor and limit switches required to give a one turn rotation drive to gear 16. A longitudinally slidable blade-bar carrying the removable lower or stationary blade of guillotine shear, is shown at 20, while at right of mill I have indicated an over-hanging type of entering live-roll table 21, on the left the upwardly swinging hinged live-roll table 22, 45 with both tables assumed to be driven by the usual reversing motors, (not shown).

Track for ingot-carriage is indicated at 23, a ring-ingot in place on roll is shown at 24, a stripper bar at 25, a partially rolled ring at 26, the latter after further rolling at 27, and an endless-belt plate at 28, passing down into the heated pit whose wall is shown at 29, surmounted by the twin gates 30 and 31, on right, and 32, 33 on left, in turn mounted upon the shafts 34, 35; 36, 37, respectively mounted in the bearing-blocks 38 and 39, and attached at rear ends to the crank-arms 40, 41, and 42, 43, of which 40 and 42, as well as 41, 43 are connected together by the cross-connecting rods 44 and 45, respectively, each having the slot 46, or 47, at left-hand end, to permit 32 and 33 to be moved further to the left whenever a rolled ring is to be removed intact without cutting, but not otherwise.

Normal directions of feed, and rolling are indicated by arrows, although all motors for such purposes are preferably made reversible, for emergencies and for occasional reversing use. Slightly oscillatable aprons are shown at 48, 49, and 50, while the position of a flat plate being run through the mill is indicated at 51.

Power-driven means for operating the twin pit-gates 30, 31, and 32, 33, is shown by the connecting-rods 52, 53, at right, but the functioning means will be explained more fully in connection with a later figure.

In all the figures identical parts are indicated by the same part numbers.

Referring now to Figure 2, new parts not previously identified comprise the main roll-neck roller-bearings 54, the thrust roller-bearings 55, stepped lower circular chock 56, mounted in stepped bushing 57, in turn seated in housing 1, the bearings being held in place on the rolls by threaded ring-nuts 58.

At the right end of lower roll, I provide the similarly stepped chock 59, and bush 60, with the stepping carried out in the same direction as before, but on slightly increased diameters, so as to permit the ready withdrawal of roll 3 and left hand circular chock 56 therethrough, without disturbing said bush 60, seated in frame or housing 1A. Roll-removing carriage is indicated at 61, carrying the flanged wheels 62, 63, 64, and 65, running on track 66 forming an integral part of the base 67. Carriage 61 is bolted solidly to chock 59, in which roll 3 is longitudinally positioned firmly by the heavy threaded ring-nut 68, drawn up lightly against or near the thrust-bearing on this roll-neck, and locked by usual means.

Carriage 61 is shuttled back and forth from left to right, by the arms 69, mounted to oscillate in the bearing blocks 70, bolted to base 71, and thrown by connecting-rod 72, revolvably carried on end of crank-pin 73, attached to large gear 74, on shaft 75, in turn actuated by appropriate motor and control to give approximately 180° rotation at a time, as determined by the limit-stop contacts 76 for right-hand travel, and 77 for left throw of arm 69, which is attached to carriage 61 by means of the oscillatable link 78.

The outboard roll-centering bearing 79 is carried in the housing 80, attached to carriage 61 in any appropriate manner, which latter also carries the automatically functional band-brake 81, designed to prevent any angular shift of roll 40 while it is out of the main mill housings. To the left of Figure 2, I have shown the usual driving spindles 82 and 83, in line with upper roll 4 and lower roll 3, respectively, and carrying the customary flukes 84 and 85, inserted within the coupling-boxes 86, 87, held in place by the usual retaining blocks 88, 89, retained by the customary iron band, (not shown).

A freely running sleeve or other bearing is shown at 90, longitudinally retained by the thrust collars 91, and pushed upward by rod 92, attached to one end of balancing-bar 93, revolvably mounted in bearing-block 94, on the concrete base 95, and carrying on other end the free roller 96, running into and out of a depressed pocket in spring 97, attached to base 95 at point 98. At an intermediate radius on bar 93 is mounted the eye-bolt 99, passing through the strong compression-spring 100, positioned by the properly drilled strap 101, and the adjusting nut 102, drawn up 60 taut until the spring 100 just balances the weight of spindle 83 and its directly associated parts, which are retained in approximately central position by the roll 96, seated in its depression in flat spring 97, whenever roll 3 is removed from the mill, and thus facilitating the re-entrance of the well-rounded flukes 103 on left end of roll 3, into the also well rounded opening in coupling-box 87, whenever roll is re-entered into the mill. The removed position of belt-plate tightening pulley or drum is indicated at 104, this device carrying the projecting nose 105, loosely fitting into the vertical channel 106 on left side of pit or well whose wall is indicated at 29, while it is itself mounted upon the heavy vertical plate 75

101, only part of which can be shown in this figure.

Referring now to Figure 3, there will be found new parts as follows: the guide-rolls 108, stepped to two diameters as shown, carried on the mounting pins 109, and running along the guide-channels 110, in turn carried by the support 111, which may be integral with bearing-block 70, if desired.

10 Above, there is shown the band-brake operating lever 112, pivotally mounted upon bracket 113, carried by carriage 61, and flexibly attached to band-brake 81 at the swivel connection 114, and all functioned by the roller 115, running more or less horizontally along the cam-track 116, bolted to the stationary base 67, and properly profiled along the roll contacting surface, to tighten up the band-brake 81 as soon as a start is made to withdraw the roll 3 from mill, and to release said roll in the last 1" or so of its return travel into the main mill housings.

This is in order to make doubly sure that the respective flukes 103 will re-enter the coupling box 81 on every return of the roll.

25 In Figure 4, in addition to parts already enumerated, there is found the bearing-block 117 for the main shear shaft 15, also the blade 118 on guillotine, and blade 119 of the lower blade-bar 20, while on the left there is the supporting tube 120, mounting the operating cylinder 121, further supported by the side bracket 122 which goes down to concrete of mill base, said cylinder containing piston 123, functioning blade-bar 20 by means of the long piston-rod 124, the right hand end or nose of blade-bar 20 being made well tapered toward the bottom side, and somewhat rounded off upon extreme end in order to promote easy entrance into housing 1A, the wear-blade 125 being inserted to make certain the entrance of bar 20 within the belt-plate, as this blade 125 is also sloped back to a wedge-end in near contact with roll 3.

In Figure 5, new parts requiring mention are, the very long, vertical hydraulic cylinder 126, located in well to rear of pit 127, which latter slopes down to one side to form the scale-pocket 128, reachable from above by crane-cable 129, carrying the grab-bucket 130, operating preferably in the small auxiliary well 131, topped by suitable doors 132. Opening into the main mill-pit 127, is a gas or other heater 133, here shown as supplied by the fuel pipe 134, and the air pipe 134A, properly valved by usual means, and therefore not shown.

55 Plate tension-drum 104 has here been shown also at a lower position 104', within the pit 127. In Figure 6 this tension-drum has been further shown in its extreme upper and sidewise withdrawn position 104', and such prime markings 60 will be used hereafter for other parts when shown in this same uppermost and withdrawn position. This Figure 6 also shows as new elements, the second and lower guide-channel 135, similar to 110, but with certain parts reversed, as shown in 65 a later figure, so that the guide-roll 136 and its companion roll 136, on rear end of same axis will enter it readily, whereas they will not follow 110 on up at all, while the guide-rolls 108, 137, 138, and their respective companion rolls on rear ends 70 of same shafts, will readily enter and follow 110, but not 135 at all, so that 108 is eventually carried well off to the right of original vertical position, but 137 and 138 remain in the vertical channel as they do not rise high enough to reach 75 the turn, and thus they always serve to centre

the plunger 139 by holding its plunger-head 140 in position.

This plunger 139 operates through a gland 141, in top of cylinder 126, on the application of suitable hydrostatic pressures thereto, as through the pipe 142, and suitable valves, (not shown, as being of ordinary type), and rises within the small side-well 143, connected with the mill-pit 127 by the very narrow slit 144 only, in which the heavy steel plate 107 slides freely, carrying the drum 104. Motor 145, on the right, functions 10 the gear or worm-wheel 14, and through it the connecting-rod 12, and arm 69, located above the side-pit 146 into which the drum 104 withdraws to position 104' at the extreme top end of its travel, while a long link 147, connecting axes of 15 rolls 108 and 137, is also shown, together with the long right-angularly mounted arm 148, solidly bolted to drum supporting plate 107, by the means 149.

20 Referring to Figure 7, it should be noted that it is a section taken just back of the front guide-channel 110, between it and the guide-rolls 108 and 136, the precise line of which was difficult to show on Figure 8.

25 Continuing under Figure 7, the function of arm 148, and the link 147, and also of the new link 150, pivoting above at pin 151, in the arm 148, and below at pin 152, in plunger-head 140, in aiding drum 104 to move over to the right to its 30 104' position, becomes evident, the final or withdrawn position being indicated for all the parts by the addition of a prime (') to the regular part number concerned in each case.

35 As the plunger 139 is then later retracted, 104' 35 quickly moves over toward the left to its 104 position, where all the parts are shown in full lines, and then the whole unit moves down together to the lower levels required in the pit, and with 104 held firmly in the horizontal position throughout. 40 A cold-air inlet is shown at C. A. I., with small motor-driven blower at M. B.

45 Other new parts first to be found in this figure are, the back guide-rolls 153, mounted upon arm 148, and the soft-metal plunger-guide-rolls 154, the mounting of which latter will be indicated 45 in the succeeding figure.

In Figure 8, additional parts consist of guide-channel 155, for rolls 153; supporting brackets 156, for soft rolls 154; the loosely-pivoted heat-seal plates 157, mounted in narrow side channel off of slot 144; the circular stiffener-block 158, mounted on plate 107, and carrying the tapered shaft 159, mounting the heavy and dry-running ball-bearings 160, 161, and 162, the first two 55 carrying the dirt sealing tube 163, which in turn supports the drum proper 164, with appropriate dust-seals at 165, 166, and 167. It will be noted that the rolls 154 ride directly upon the hydraulic plunger 139, without interference with other 60 parts, so that as many of these rolls as desired may be spaced along the line of travel of the very long, and otherwise insufficiently aligned plunger just mentioned.

65 In Figures 8A and 8B no new parts appear requiring identification.

In Figure 9, the pivot-pins for seal plates 157 are shown at 168, and the side-channel or slot in which such plates operate, is indicated at 169, while their mode of recession and return as plate 70 107 passes up and down, is indicated at top.

In Figures 10 and 11, no new parts appear which require identification.

75 Referring now to Figure 12, a means for pulling the swinging twin-gates 32 and 33 still fur-

ther to the left to about the limit positions 32' and 33', after hinged live-roll table 22 has been lifted up out of the way, is shown at 170, 171, the propelling means being preferably a motor and 5 $\frac{1}{2}$ revolution reduction gear, similar to that to be described a little later on, for the normal up-and-down motion of both sets of gates, but omitted in the case of the connecting rods 170 and 171, because of space limitations on the drawings, and because these latter rods can be moved 10 over in unison, thus utilizing well known elements, not appearing in my claims. This further swing of these left hand gates only, is to provide for the withdrawal of endless rolled belts or rings 15 from the mill, whenever such appear on a customer's order, and the lost-motion links 46 and 47 have been provided to permit the added gate travel, whenever required.

It will be noted that arms 42 and 43 are keyed 20 to shafts 36 and 37, so as to bring gates 32 and 33 to the full-line positions shown for the latter, respectively. Suitable counterweights for the twin-gates 30, 31, 32, 33, are indicated at 172, 173, 174, and 175, respectively, these being preferably 25 back in a pocket off to rear of main mill-pit. Mounted upon a heavy pin 176 attached to left side of housing 1 is the heavy extension spring 177, suitably attached at its lower end to the swinging apron 50 already mentioned, so as to 30 lift the latter whenever guillotine 11 rises toward its upper position, as it is shown in the process of doing in the figure. This is to prevent any plates emerging from rolls 3, 4 from getting entangled with said guillotine. Fitting within an 35 arcuate recess on right side of blade-bar 20, but in no wise connected therewith, is the lower swinging-apron 178, pivoted at its left centre so that it may rise to the 178' position, into contact with upper mill 4, or approximately so, by any 40 usual means (not shown). It will be noted that right-hand swing-apron 49, may be raised similarly to position 49', whenever desired, as when endless-rings are being rolled, or lowered for flat 45 plates, to the full-line position shown, with the sharp end portions of both 49 and 178 resting lightly upon the lower roll 3, and constituting the necessary strippers therefor. A ring-edge guide-roll is shown at 179, mounted upon the end of 50 long adjustable stud 180, which will appear more in detail in a later figure. Ring side-guide plates are shown at 181, 181A, and 182, provided with screw-adjustment studs 183 to 188 respectively, passing through housing 1 so as to permit adjustment from the outside thereof. At 189 I have 55 shown a powerful electro-magnet, with all projecting corners well rounded off as indicated at 190, and associated with a similarly rounded heavy metal-bar 191, from which depends the heavy pivoted-link steel chain 192, articulated by 60 the pins 193, so that if required it can peel off the magnet 189 and back through the arc 194 toward the lower mill roll 3, whenever a plate gripped between said magnet and chain is being drawn up from the pit and out through the mill 65 rolls to the live-roll table 22, at the left, after such plate 28 has been cross-cut by the shear 11, or equivalent means. It will be noted that plate may be bright red hot at the time it must be sheared, so that magnet must be powerful, and 70 able to firmly grip the heavy steel chain, even through the interposed thickness of non-magnetic plate. This has been calculated out and found to be entirely within the usual safe limits. Magnet 189, bar 191, and chain 192, are all mounted 75 on a carriage which can be quickly thrust

through the opening 195, in housing 1, or retrieved therethrough, by any convenient piston or motor actuated means, such as that shown for bar 20, in Figure 4, for example, and indicated by the part-numbers 120 to 124, inclusive.

As 189-191 will have to carry from 5,000 to 10,000 pounds of plate weight, possibly, it is preferable to enter a nose on the end thereof into the remote housing 1A, just as in case of bar 20, to give added support.

Below housing 1, and a little to right of its centre-line, I have provided the additional opening 196, through which, by means similar to that just cited, the slitter frame 197, which projects well out beyond its carriage 198, mounted upon the wheels 199, and tracks 200, may be projected within the mill and between the housings 1, 1A, whenever required for plate slitting or spiral-cutting purposes.

The power driven rotary slitting-cutters are 20 shown at 201, 202, these being mounted within the long, projecting horse-shoe shaped mountings 203, 204, the plate-entering ends of which are deeply V-shaped or beveled-off as indicated by the shading, so as to permit ready and certain entrance over the plate-edge, without any hesitation. Cutters 201, 202 are slightly drawn apart 25 during this entering operation, and then closed down upon the plate, but as the means for accomplishing this motion is not covered by my 30 present claims, it will not be further gone into here, only enough being shown to illustrate the general application of a longitudinal slitter to my mill.

At right of figure, a large reduction gear 205 35 is mounted upon shaft 206, bearing on its opposite outboard ends the two angularly spaced crank-arms 207, and 207A, all carried by bearings in the long pedestal 208, which is mounted alongside motor 209, on the common base 210, and 40 which motor carries the pinion 211, meshing with the gear 205. Crank-arms 207, 207A, mount the crank-pins 212, 213, which, for a half revolution in counter-clockwise direction, of the gear 205, move to the points 212' and 213', respectively, 45 and through connecting-rods 52, 53, carry down first the gates 30 and 32, to their 30" and 32" positions, respectively, then following with the upper gates 31, 33, to the 31" and 33" positions shown therefor. This closes off the pit top, ready 50 for entrance of ingot-carriage along track 23, but without much loss of the pit heat into the machinery and room space above. A later half-revolution reversal of gear 205, as per dotted arrow, restores these gates to the position for rolling a new ingot and plate-belt, again without material loss of pit contained heat. Above the live-roll tables 22 and 24, I have shown the power-driven reeler drums 214, 215, to left and to right, respectively, mounted on the heavy shafts 60 216, 217, carried by the pedestal bearings 218, 219, each drum containing the automatic plate grip 220 or 221, firmly gripping the two ends of plate or sheet 222, while tension may be applied to either trailing drum by the brake 223, or 65 224, for the two reelers respectively, which are mounted slidably upon the bases 225, 226, so that the entire unit can in each case be withdrawn back from the plane of the paper, whenever no reeling 70 is to be done, as in the case of the thicker sheets and plates. A cradle for the live-roll transport of a fully reeled sheet is shown at 227, but as these parts may be included in a later patent application, they will not be further elaborated upon 75

here, having been shown simply to show the wide diversity of applications of this type of mill.

In Figure 13, I have shown as an alternative means for cross-shearing the belt-plate, the insertible rotary-shear structure 228, consisting of a more or less horse-shoe shaped heavy frame, well beveled away at points 229, for easy entrance upon the plate, and containing the two rotary cutters 230, 231, power-driven by the chain drives 232, or equivalent means, and capable of quick insertion through and return via the opening 233, just below or even possibly within the housing 1, the inserting means being similar to that already described in connection with the blade-bar 20, of Figure 4, under items 120 to 124, inclusive, or their equivalent.

Several of the openings 233, 233A, 233B, and so forth may be provided, if desired, in one of which 228 may be placed to operate, according to the 20 ring diameter then being rolled, as 27, 27A, etc., or I may elect to provide where it will not interfere with other elements, a swinging arm 234, mounted upon shaft 235, in bearing-block 236, and carrying at its extreme end the loose roller 25 231. Arm 234 may be pivotally connected at 238, to connecting-rod 239, attached to crank-pin 240, on large reduction gear 241, carried by shaft 242, and in turn driven by small pinion 243, mounted on shaft 244 of an appropriate motor, 30 (not shown), and all used as a means for forcing the rolled ring 27, or 27A, down and over to the right, until it can be easily entered upon by the shear mechanism 228. For belts which are drawn taut by the drum 104, as it goes down to final 35 104" position, arm 234 will not be required.

In every case, before cutting open a belt-plate, it should be firmly clamped just below the shearing means, as by the clamping jaws 245, 246, 40 which are run in from back of the housing 1, by means similar to that already cited in connection with shear 228, and the open jaws then closed down as indicated by the small arrows, and by any well known means, such as a motor driven toggle-joint, for example, so as to clamp 45 the plate firmly before shearing, ingress and egress being through the opening 247, to rear side of mill, which opening may be repeated to the left of that shown, if desired, as at 247A and 247B, so as to accommodate 233A, and 233B, if necessary.

As a second alternative plate cutting means, I have indicated an air-tube 248, containing the smaller gas-tube 249, and mounting the oxy-acetylene burner, or burners 250, all of which 55 may be progressed slowly across the sheet by piston or equivalent means, similar to that previously cited, and then rapidly withdrawn back into or through the wall of housing 1, after the cutting.

60 Figure 14 shows new parts comprising the tail-end sprockets 251 and 252, with their appropriate shafts mounted in the U end of frame 229, while a chain-clamp enveloping both chains 232 is indicated at 253, with clamping-bolt 254, mounted 65 at projecting end of rod 255, whose attachment to base will be indicated in a later figure. A piston-rod for propulsion of carriage 228 is shown at 256, while 257 indicates one of the four mounting wheels of latter carriage.

70 Chain-housings of thin metal are indicated at 258, left and right hand mill-pit limit lines are shown at 259 and 260, respectively, or about the belt-plate width.

In Figure 15, guiding and track channels for 75 the wheels 251 are shown at 261, mounted on

the arcuate sub-base 262, slotted at 263 for the clamping-bolt 264, tapped into metal base 265, made arcuate to match 262.

In Figure 16, a vertical pedestal integral with sub-base 262 is shown at 266, firmly bolted to 5 bar 255 at 267, this pedestal also supporting the long hydraulic cylinder 268, enclosing appropriate piston, (not shown), for actuating the rod 256.

Figure 17 contains no new parts requiring further identification, but in Figures 18 and 19 there is found the heavy threaded stud 269, which may recede into recess 270 in the mill-housing 1, and which stud is carried by the internally threaded heavy thrust bushing 271, 15 which is also threaded part-way on outside for spur-gear 272, keyed to bushing by the threaded and lock-washer bolt 273, while bushing end is carried within the stiff mounting frame 274, 20 275, bolted together and to housing 1 by heavy bolts 276, and long key-slot 277 in stud 269 is slidably keyed to frame 274 by the long key 278 shown in Figure 19 only, which latter also shows a driving-pinion 279, meshing with gear 272, and in turn driven by shaft 280, of any suitable 25 motor. One of these longitudinally adjustable studs, mounting guide-roll 179, will preferably be positioned on each side of the mill, close to edge of the material.

In Figure 20, a composite mill-roll for rolling 30 circular ingots 24, is made up of a heavy, ultra-hard, special alloy-steel outer shell 3A, a plurality of heavy, heat-equalizing copper cylinders 281A, 281B, with one or more intermediate steel shells 281C interposed, and all pressed tightly within 35 shell 3A, and over the inner forged or cast-steel shaft 282, which may or may not be drilled through at 283, for water-return from the within-roll end of stationary, concentric water-supply tube 284.

Figure 21 shows this tube 284 as centralized by the outside support 285, and as located inside of the part-length multiple layers of metal tube 286, provided for further longitudinal heat 40 equalization purposes, while the extreme left-end of the drilled hole through shaft is plugged up by the means 287, and the roll-driving flukes are indicated by dotted lines 288. The opposite end of roll-shaft proper 282 may be in one piece therewith, or in some cases it may consist of a 50 shaft extension 289, coarsely taper-threaded at 290 to fit corresponding thread in shaft 282, and held firmly in place by a longitudinally drilled key, or the lock-washer bolt means 291, while the extreme outer end is threaded at 292 for plug 55 bushing 293, whose end-surface 294 may be made arcuate to take the spherical face of a carbon, graphite, or other slip-joint for water return connection, (not shown). The copper rings 281A and 281B may be well riveted over into the 60 bevels 295A and 295B, provided around ends of parts 3A, 281C, and 282. The "puffing out" of mill-rolls, which results in considerable differences in thickness across the width of plates being rolled, is not due to roll temperatures encountered, per se, but to "differences in temperature" along the roll face, and radially inward therefrom, which also co-incidently introduce tremendous longitudinal breaking strains in axial portions of any one-piece type of roll, but not in 65 the roll of my invention, so that the latter may be water-cooled internally without injury, if so desired. The copper shells constitute transverse heat equalizing paths, from 8 to 15 times as good in heat-conducting ability, as equivalent 70 75

masses of steel-alloy parts, and the layers introduce a multiplicity of joints, giving radial heat obstruction.

5 The tubular metal layers 286, within drilled hole 283, may also be used to shade and help equalize the heat abstraction by the cooling water, since multiple layers of thin metal form poor heat conductors transverse to the plane of sheets.

10 These can be later adjusted conveniently to vary the maximum cooling positions, as indicated by any remanent puffing found, the tubes shown being replaced by others of the different lengths best suited to give the equalization required, but all made of highly heat-conducting material, such as copper, as a preferred form.

In Figure 22, besides elements already enumerated, there is found the ingot-carriage or buggy 296, mounted upon the flanged wheels 297, driven by motor 298, operating through the reduction gears 299, and all running either on the track 23 entering in under the live-roll table 21, or on the higher track 23' extending out to right from extreme end of table 21 only. A ring ingot 25 24 is carried by the rollers 300 and 301, the former of which is slowly rotated by appropriate gears 300A, driven by main gear train, so as to prevent cold spots in the ring in transit, and both rolls are carried by the projecting arm 302, back of 30 which is the raisable cantilever-arm 303, functioning around the axis 304, and pressed down on its right hand end by the oscillating cylinder and piston 305, until said cylinder is in 305' position, and connecting-point 306 on end of piston has 35 moved down to 306', forcing opposite end of arm up to the 303' position, and with it the ring 24 to 24', ready for re-insertion of the mill roll as indicated by dotted-line circle 3A.

Top face of carriage 296 is composed of the 40 live-roll train 307, functionable in the direction of rotation indicated, so as to run flat slab 308 off to left when carriage is delivering such slab to extreme right end of table 21, via track 23'.

45 Stiff cross-beams between the rolls of table 21 are shown at 309.

As indicated in Figure 23, these cross-beams 309 have side projections at the outboard-end 310, supporting roll 21 in the bearing-block 311, the roll being carried at opposite end by similar 50 block 312, beyond which on roll shaft is the pair of mitre-gears 313, 314, the latter on shaft 315, mounted by a bearing attached to the projecting foot 316, integral with beam 309, and all mounted 55 upon base 317.

On other side of pit, a supporting bracket 318 carries the insulated and inverted third-rail 319, contacted with by the spring actuated shoe 320, for supply of electric power to the ingot-carriage, 60 this shoe being of course well insulated from frame.

65 Preferably this third-rail should have been placed on right side of pit, however, and with obvious alterations of structure. Ordinarily the slab 308 will not be present, when carriage 296 is run in under the mill, on track 23, nor will ring 24 be present when track 23' is being utilized, as for the delivery of hot slabs.

70 This automatic ingot-carriage 296 has been shown in order to complete the picturization of my mill and its associated mechanisms, but since this carriage has been made the subject of a separate application for U. S. Patent, under Serial 75 #652,142, filed January 17th, 1933, it will not be

further elaborated upon herein, or included in the present claims.

The circular ingot required for use in my present mill will preferably have been centrifugally cast and "jarred" in the apparatus covered by my application Serial #680,570, filed July 15th, 1933, and heated in my furnace as per application Serial #655,185, filed February 4th, 1933.

In Figure 24, there are no parts to be identified, but it will be noted that the rolling velocity at any given part of the rolling operation can be made absolutely independent of that at any other part of the total process, so as best to shorten up the total rolling time, and tend to keep the horsepower input within a desired range of values. This can not be done with the multi-stand continuous mill, for the ratio of speeds among the various stands must be substantially fixed, once the rolling gets under way, by the longitudinal extensions of the sheet at each set of rolls, and the more lightly loaded rolls can not be speeded up as much as desired, without throwing tremendous overloads upon the more heavily worked stands, and their motor-driving equipment.

In Figure 25, a wide continuous belt-plate similar to 28 of Figure 1, is shown after peripheral slitting, as by the cutters 201, 202, of Figure 12, into narrow continuous bands 321.

Figure 26 shows the same belt-plate 28 after spiral slitting by my spiral slitting mechanism, as covered by separate application previously referred to, and producing the ultra-long spiral single strip 322, which may be run out onto the reel 214 shown on Figure 12, as the slitting proceeds.

In Figure 27, the inter-roll beam 323, instead of being made integral with the base 324, as was the case for 309 and 316 of Figure 23, is separated therefrom, being mounted upon the flat 325, and also upon the outboard bracket 326, attached to base 327. Beam 323 also is integrally cast with the projecting crank-arm 328, drilled to swing around shaft 315, running in a heavy bushing attached to base 324, 328 being integral with the counterweight 329, so that both 328 and 329 are 45 functioned by the connecting-rod 330, attached to 328 and to the arm 331, mounted upon shaft 332, in bearing-block 333, and driven by the worm-wheel 334, and worm 335, on shaft of motor 336, appropriately controlled to swing roll 22 to about 50 the 22' position and stop, and return later on when required to the full line position 22.

With roll in the 22' position, counter-weight moves to position 329', and arm 331 may be designed for exactly $\frac{1}{2}$ revolution steps, if so desired.

Supplementing the description given in connection with Figure 4, it may be noted that the extreme protruding tip of bar 20, at the right, and the small side pin shown mounted upon upper right side of gear 16, will be used to function limit switch contacts exactly like those shown at 76 and 77 of Figure 2, connected to prevent starting up of gear driving motor until bar 20 has been rammed in fully to the right, as shown, and likewise causing the immediate return of this bar to the left, or withdrawn position, as soon as gear 16 has made a single revolution and stopped, under the action of its own contact points connected to the shunt coil of gear-motor controlling contactor. Similar contact means will be utilized to make certain that mill is stationary, and motor controls open, before either the guillotine 11, or the rotary-shear 228 may be allowed to function.

Like contact means will be provided to cause release of plate clamp jaws 245, 246, of Figure 13, and to cause the recession of carriage mounting these jaws back within the base under housing 1, before interference can develop as drum 104 is raised up from bottom of the pit, and also to prevent insertion of these jaws under the mill rolls again, until said drum has passed the 247 position on its road down again, with a succeeding belt-plate. Further similar contact means will be utilized to prevent drum 104 being run in from its withdrawn or 104' position, until each successive new rolled ring has been lengthened out to a suitable clearance position, or until long enough to receive said drum readily without danger of fouling therewith.

Similar safety provisions will be made for preventing entrance of slitter 197, or of magnet parts 189 to 192, also of ingot-carriage 296; and for the swing of table 22, of Figure 27, or the gates 30 to 33 of Figure 12, until such times as will obviate interferences developing with other moving parts. As all these contact means will be simple duplications of parts 16 and 17 of Figure 2, they have not been repeated on the other drawings, in order not to clutter up the sheets with repeat sketches, particularly as the type of connections used is well known in the art. In the aggregate, however, these devices tend to make the operation of my mill substantially fool-proof, so far as possible interferences are concerned.

I am perfectly aware that many disclosures have been made heretofore, covering the rolling of rings or bands, but if an attempt is made to apply these disclosures to the production of an actually commercial mill, it is found that many important elements which are absolutely essential to a really comprehensive and satisfactory design, are either entirely missing, or abortive in their showing, or develop interferences with other parts, when assembled in a complete mill design.

I have attempted to remedy these deficiencies and provide a commercially operable continuous belt mill, retaining the very important inherent advantages accruing to this type of machine.

Thus I am able to readily provide for the commercial rolling of either ring-ingots or flat-slabs, in one and the same machine, and to deliver either large diameter rolled belt-rings, or very long flat plates, or sheets, and to accomplish various cross-cutting, slitting, spiral cutting, annealing, and delivery operations thereon, whereby a wide diversity of product is assured, at high output tonnages per diem, from a single-stand mill running at high speeds, so that the rolling may be accomplished at high rolling temperatures and therefore with less destructive strain upon the metal than is usual in other mills, and further reductions accomplished under initial heat than is customary, while provisions have been made for retaining or even increasing the plate temperature during the actual rolling, if desired, and for keeping the belt taut during such rolling, as this accentuates the reductions possible to attain at a single rolling.

Such tension operation is not claimed as new, however, as it seems to have been first definitely provided for by Cox, in U. S. Patent #600,359, of 1898.

Many of the references show overhung-types of rolls, which are eminently suited to insertion or withdrawal of ring-ingots or belts, but are hardly considered a commercial type of roll for the production of really wide belt-plates, under regular mill conditions, because of working flex-

ure, roll-fracture, and roller-bearing shortcomings in the single roll-neck utilized for bearing purposes here.

Thus many of the references which might be cited show some one or more of the features contemplated by me, but leaving much that is wanting in regard to the satisfactory commercial operation of the whole, as a complete mill assembly.

For ring-ingots weighing from 8,000 to 15,000 pounds, for example, the horizontal types of tension mechanism become impractical altogether, as it is highly desirable that the outgoing and return sides of the belt do not contact with each other at all, since hot-metal surfaces in high-speed rubbing contact score up badly, and ruin the plate surfaces for many usual purposes.

None of the references available show a really commercial means for getting a tension drum inserted within a gradually enlarging belt-plate made from a heavy ring ingot, of the type I 20 contemplate, and for the proper withdrawal of such drum out of the sphere of action until the completion of the early stages of ingot rolling.

One or more references have briefly referred to the possibility of heating the belt by gas or 25 otherwise, during the actual rolling thereof, but I have shown a commercially operable mill-pit for attaining this end under actual operating conditions.

I have provided a practical plate-type seal, and 30 a blower mechanism, to keep the hot pit gases out of the drum, elevating hydraulic plunger compartment.

I have provided a tension drum mounted upon very much over-sized ball bearings of temperature 35 resistant steel, so that they can be operated dry, in the heated area. My invention also contemplates means whereby the heating of the belt during rolling shall not imply devices which seriously interfere with the insertion of the successive new ingots, or the delivery of cut belt-plates 40 from the mill, or the withdrawal of endless rolled ring-belts, if desired. I prefer to retain very large percentages of burnt or inert gases within the heated top portions of my mill-pit, so as to 45 greatly reduce the normal amount of scale production during rolling, it being evident that the ring-belt emerges into contact with normal atmospheric gases for only a brief moment as it passes over the lower mill roll, and furthermore, 50 that the number of cold rolls with which it comes into contact in each circuit around the mill, is reduced to the very ultimate minimum, in wide distinction to customary flat plate rolling practice, where it meets a multiplicity of cold 55 metal roll surfaces, and water-sprays, all of which greatly reduce the rolling temperature, and prohibit high ultimate reductions, at the same time vastly increasing the work of rolling.

On customary mills the scale loss, although 60 only about 1½% to 2% of the metal rolled, yet totals a tremendous annual aggregate, where a mill is in continuous operation, because of the great tonnages handled. A large fraction of this I propose to save, by the means just indicated, 65 and amounting to from \$20,000 to \$50,000 or more per annum for a large mill in continuous operation, if this were possible.

The belt-plate also eliminates the customary "fish-tail" cropping losses, often amounting to 70 twice this much per annum, even after allowing for the re-melt value of the scrap produced. The use of a tension-drum within the belt being rolled, tends to substantially eliminate the usual side camber, which is also a serious source of 75

trimming loss in customary flat-rolled plates.

The use of centrifugally cast and "jarred" ring-ingots results in extremely dense, clean, gasless, and solid metal, free from non-metallics, and eliminating the usual 12% to 15% or more "cropping" loss, common to the usual straight ingot, thus again cutting the total cost, and increasing the quality of plates produced by the apparatus of my invention.

10 Since ring-belt plates can be rolled to about 3 times the length and tonnage each of flat plates made from the usual slabs, my belt-plates when opened out flat, will provide blanks for electric tube welding which will cut welding end-scrap

15 losses to a previously unheard of low value, of vital importance to the pipe manufacturer.

The substantial elimination of scaling should produce plates and sheets, which, though hot-rolled, are remarkably free from surface blemishes, and very smooth.

20 All these points represent important manufacturing advantages, which in their aggregate represent quite an advance in the art, and a considerable cut in costs.

25 It is believed that the general mode of operation of the several elements of my mill and its associated equipment described herein, will be self-evident to anyone skilled in the art to which my invention appertains, without elaborate description thereof, and such further explanation is therefore eliminated, in the interest of brevity, and in view of the rather lengthy presentation already given.

While I have herein illustrated and described 35 a preferred embodiment of my invention, and alternative constructions of certain parts thereof, it will be understood that moderate changes in the construction and arrangement of the parts may be made without departing from either the 40 spirit of my invention, or the scope of my broader claims.

As an indication of the enormous gain in tonnage incident to this method of rolling, as compared with the old single-stand plate mills of 45 usual type, it may be stated that, whereas 60 tons of $\frac{1}{8}$ " sheet product per 20-hour day is a good output for one of the latter mills, the mill of my invention is capable of about 1200 tons output in the same period, on the same thickness of 50 product.

The ring-ingots I propose to use are much heavier than the flat-slabs used by customary mills, and the ready maintenance of initial rolling temperatures by my heated pit permits far 55 greater rolling speeds and reduction percentages per pass, and also reduces the usual plate overweight allowance due to spring of the rolls, since this springing is far less in the case of the hotter sheet, allowing the sheets to come through more 60 uniformly to accurate gauge, with consequent saving of material.

But although especially adapted to the hot rolling process, my mill may also be used equally well for cold rolling, without heat in the mill-pit, 65 if so desired.

As my new roll, Figures 20 and 21, has been made the subject matter of my co-pending application, Serial #682,581, filed July 28th, 1933, it does not appear in the present claims, but has 70 been shown in order to round out the presentation of the mill as a whole.

In connection with Figure 8b only, it should be noted that at the point where smaller guide-channel 135 takes off to the side from its vertical 75 position, as perhaps better indicated in the ele-

vation thereof shown on Figure 6, the wider portion of complete guide channel must be cut through on one side, just sufficiently to let the shaft mounting roll 135 pass therethrough. This slot is sufficiently narrow, however, to permit the large rolls 108, 137, and 138 to easily bridge it, when they pass by here later on. Below the lower track junction point with 135, the vertical guide-channel will present the section shown in Figure 8, including the two steps, as brought out by the 10 dotted additions to Figures 8a and 8b, incorporated therein in order to give the horizontal placement of the respective channels.

What I claim is:

1. In a continuous belt rolling mill, the combination comprising a plurality of substantially parallel and closely spaced work-rolls, power-driving means for said rolls and including a readily disconnectable coupling member providing drive connection to one thereof, weight balancing means on the said coupling member, a roll withdrawing carriage attached to the disconnectable roll at opposite end thereof, and an automatic roll clamping means mounted upon said roll withdrawing carriage.

2. In a continuous belt rolling mill, the combination comprising a plurality of parallel work-rolls, a pair of spaced mounting housings therefor, a belt runway adjacent said housings, a power-progressed belt tension-drum operative longitudinally of said belt runway, transverse and longitudinal guiding means for said tension drum, and including means for transverse withdrawal of said tension-drum near mill end of runway.

3. In a continuous belt rolling mill, the combination comprising a pair of spaced mill housings, a plurality of substantially parallel power-driven work-rolls mounted between said housings, a power-operated roll withdrawal and re-inserting means operatively connected permanently to one of said work-rolls, a power-driven ring-ingot transporting and entering means operative transverse to axis of one of said work-rolls, and containing a ring-ingot lift means operative to centre ring-ingot with roll axis substantially, a track 45 for said ring-ingot transporting means attached permanently to inside faces of said housings and which substantially spans the belt rolling space in mill, and a mill entering live-roll table of the over-head type and mounted to provide suitable 50 clearance for said ring-ingot transporting means over said track.

4. In a continuous belt rolling mill, the combination comprising a plurality of parallel power-driven work-rolls, a mill housing mounting said 55 work-rolls, a belt runway adjacent said rolls, and a belt tension-drum progressive by power along said runway, including drum diverting guide means positioned to automatically withdraw said drum from said runway on approach to said rolls 60 and re-enter the same on the reverse motion.

5. In a continuous belt rolling mill, the combination comprising a pair of parallel mill work-rolls, a roller mounted roll-withdrawing carriage operatively connected permanently with one of 65 said work-rolls, a precision-throw device connected to said carriage to give a precise longitudinal travel thereto during roll withdrawal and re-inserting operations, and an automatically operable positive roll-brake functional by the roll-withdrawing carriage just after start of its withdrawing stroke, and automatically releasable substantially at end of the return of roll into mill, a cam to close and open said brake being included herein.

6. In a continuous belt rolling mill, the combination comprising a substantially parallel pair of mill work-rolls, a roller mounted roll-withdrawing means permanently connected operatively with one of said work-rolls, a separable coupling member in the drive mechanism for the latter work-roll, and a positively operable automatic brake mounted on said means and operatively connected with said latter work-roll, and operable by a stationary cam included herein, to preclude accidental rotation of coupling elements during their separation, and until their return into mesh, as roll is replaced.

7. In a continuous belt rolling mill, the combination comprising a plurality of substantially parallel mill work-rolls suitably supported in mill-housings included herein, a power-driven roller-mounted roll-withdrawing means operative to retract one roll longitudinally through a window in one of said housings, an ingot delivery means operable between said housings on spaced tracks mounted thereon, and interlock contacts connectible to signal said delivery means to enter when said one roll is fully withdrawn, and to signal again when it is later fully replaced, so that said ingot delivery means may be then withdrawn.

8. In a combined slab rolling and continuous belt rolling mill system, the combination comprising two substantially parallel spaced mill work-rolls, a pair of mill housings supporting the said work-rolls in variably spaceable relation, a flat live-roll table mounted to feed and discharge flat slabs between said work-rolls when desired, ring-ingot delivery means operative under said live-roll table to deliver ring-ingots in line axially with lower work-roll of said mill when desired, widely spaced tracks mounted between said housings to carry said delivery means along a path transverse to said work-rolls, and a roller-mounted roll-withdrawing carriage connected operatively with said lower work-roll and adapted to retract the same longitudinally a precise distance, by power means also included herein.

9. Claim 8, characterized by the addition of interlock contacts contactible by said roll-withdrawing carriage at the end of its retracting motion, to signal through known means to operator of said ring-ingot delivery means.

10. Claim 8, characterized by the addition of interlock contacts contactible by said roll-withdrawing carriage at the end of its retracting, and its return motions, separately, for signalling purposes.

11. In a combined slab and continuous belt rolling-mill system, the combination comprising two parallel mill work-rolls, a pair of mill housings mounting the said work-rolls in variably spaceable relation, a flat live-roll table mounted to feed and discharge flat slabs horizontally between said work-rolls when desired, a power-driven ring-ingot delivery means operative under said live-roll table and adapted to deliver such ingots centered axially with the lower work-roll of said mill when desired, along tracks likewise included herein, a roller mounted work-roll withdrawing means, power-driving means therefor which is operative over a precisely determined length of travel, and a vertical-motion cross-cut shear of power-driven type mounted upon and between said housings and operative across the top plane of said live-roll table when required.

12. In a continuous belt rolling mill, the combination comprising a pair of substantially parallel mill work-rolls, a pair of spaced mill housings

mounting said work-rolls, a deeply excavated belt runway over which said mill housings are mounted, a power operated tension-drum automatically self-enterable within said belt while the latter is under motion and said work-rolls are functioning, guides for said tension-drum which are directed to longitudinally divert the same away from said belt runway as said work-rolls are approached, but vertically in line therewith at all greater operative distances, and a power propelling means for said tension-drum which is mounted in the clear of an accidentally broken belt.

13. In a continuous belt rolling mill, the combination comprising two substantially parallel and variably separable mill work-rolls, a pair of spaced mill housings mounting said work-rolls, a readily separable coupling-member longitudinally aligned with one of said rolls, a roller-mounted power-driven carriage connectible to one of said work-rolls to longitudinally withdraw the same from between said housings, a cam-operated brake mounted to prevent rotation of said work-roll while withdrawn from said coupling-member, and to free the same automatically on the full return thereof to coupled position, a cam co-operating with said brake, and an automatic balancing means for holding the drive end of said coupling-member in alignment with work-roll axis while the said work-roll is withdrawn.

14. In a continuous belt rolling mill, the combination comprising two substantially parallel and variably spaceable mill work-rolls, a pair of mill housings mounting said work-rolls, a substantially vertical belt runway beneath said work-rolls, a power-operable tension drum mounted for vertical travel within lower part of said runway, and guideways to deflect said drum automatically to one side of said runway as said work-rolls are approached by said drum, so as to clear the space normally occupied by said belt, after completion of the rolling thereof.

15. In a continuous belt rolling mill, the combination comprising two parallel and variably spaceable mill work rolls, a pair of mill housings mounting said rolls, a substantially vertical belt runway beneath said work rolls, said runway being characterized by an enlarged upper section for the rolling of large diameter rings, and an elongate lower element for the accommodation of a power operable tension drum which is also included herewith, and the lower portions of a fully rolled long belt, said tension drum including power means and guides for entering it automatically into interior of a newly rolled one of said rings as said drum is lowered from its topmost position.

16. In a continuous hot belt rolling mill, the combination comprising a means for rolling an enlarged metal ring, a power means and guide means operable to enter a tension-drum about axially within said ring while still maintaining the rolling process thereon, said tension-drum being rotatably mounted, and also claimed herein, and further means for guiding said tension-drum away from said means first mentioned to convert said ring into belt form as the rolling progresses, and to maintain the required tension on said belt during such rolling, said power means and guide means together providing means for the retraction of said tension drum away from the space occupied by said belt after said rolling is completed.

17. Claim as in 16, characterized by the addition, that said power means and guide means are both mounted substantially outside of the belt

rolling space, so as to remain disentangled from any accidentally broken belt.

18. In a combined flat-slab and continuous ring-ingot hot rolling mill, the combination comprising a pair of substantially parallel and variably spaceable mill work rolls, a pair of mill housings mounting said rolls, power-drive means

- 5 for said rolls, a live-roll feed table operable to enter flat slabs between said rolls, ingot delivery tracks mounted between and upon said housings and substantially transverse to axis of one of said rolls, said tracks entering under said live-roll table, and providing means of entrance into mill of a ring-ingot delivery means, without changes
- 10 in said table, a power means for withdrawal of one of said rolls longitudinally by a pre-determined amount and the precision return of the same, a balanceable coupling-member on opposite end of this one roll, a substantially vertical belt runway under said rolls, a heating means applied to said runway, and a power-driven and substantially vertical cross-shear applicable to cut either flat plates on said live-roll table, or hot belts rolled in said runway, without structural changes
- 15 20 25

19. In a continuous belt rolling mill, the combination comprising two substantially parallel and variably spaceable work rolls, two housings therefor, a substantially flat topped live-roll table operable to feed flat slabs into said mill and between said work-rolls, means for entry of ring-ingots over one roll of said mill when desired, and a cross-shear adapted to shear either rolled plates on said table, or closed belts rolled from 30 35 40

35 said ring-ingots, without alteration of shear parts, said cross-shear being mounted for vertical motion, on said housings, and including one longitudinally withdrawable blade element, adapted to be entirely removable from the belt

40 rolling space, by power means included herein.

20. In a continuous hot-rolling belt mill, the combination comprising two substantially parallel mill work-rolls, a pair of mill housings mounting said work-rolls, a closeable belt runway extending transversely to axis of one of said work-rolls, heating means applied to said runway, power operated gates operative to separate said work-rolls from the heated portion of said runway when required, and a power-driven tension drum, 45 50 55

50 including guides for self-entering said drum about axially thereof into a partially rolled belt without interruption of the rolling operation thereon, and further guide elements operative to direct said drum transversely to axes of said work-rolls, to apply tension to said belt.

21. Claim as in 20, but in which said runway is characterized as being enlarged at points close to said mill work-rolls, to permit the rolling of large diameter rings.

60 22. In an ultra-high-capacity single-stand continuous belt-rolling mill, a belt runway elongate in a direction transverse to mill roll axis, a tension drum enterable about axially of itself into said runway near the mill end thereof, and then deflectible in direction of said runway, guiding means to determine the course prescribed, power means operable to propel said drum into

said runway and then along the same, without manual intervention during the successive steps, said guiding means and said power means being mounted in an auxiliary channel to one side of said runway, heat protective elements to protect 5 said two last mentioned means from the major portion of the runway heat, and a means operative to cool said auxiliary channel as required, and eject leakage hot gases therefrom.

23. In a high-capacity combined flat sheet and continuous belt rolling mill, two substantially parallel and variably spaceable work-rolls, a pair of mill housings mounting said work-rolls, a flat live-roll table horizontally aligned with the work space between said work-rolls, a runway below 15 20 25 said work-rolls to accommodate metal rings enlarged during the rolling thereof, and a power lifting means applied to said live-roll table to clear said rings when latter are to be removed from mill unsheared.

24. In a high-capacity combined flat sheet and continuous belt rolling mill, two substantially parallel and variably spaceable mill work-rolls, a pair of mill housings mounting said work-rolls, a flat live-roll table mounted horizontally on each 25 side of the work-space between said work-rolls and in working alignment with said work-space, a runway directly below said work-rolls to accommodate metal rings and belts during the rolling thereof, a power shear adapted to cross-shear 30 said rings and belts, said shear containing one blade element which is retractable by power to clear entirely the said runway, when required, said blade element and the power retracting means therefor being also included herein, a 35 power driven reeler including means for gripping an end of a sheared belt and coiling up the same under tension so as to permit further reduction in thickness after maximum length attainable in said runway has been attained, and a power operated slide mounting said reeler and adapted to withdraw the same along a line about parallel to that of work-roll axis, and so as to substantially clear said live-roll table, when required.

25. Claim as in 19, with the addition of a belt 45 clamping means operable to clamp said belt near said work-rolls and before shearing, so as to obviate falling of this end of said belt into bottom of said belt rolling space after completion of the cross-shearing operation, and a power retracting 50 means operable to withdraw said clamping means from said belt space when required.

26. In a continuous belt rolling mill, a substantially vertical belt runway located below said mill, a belt tension drum operable by power within said 55 runway and to and from said mill, and an auxiliary scale receiving pit located adjacent said runway and connected by cross passage therewith.

27. In a continuous belt rolling mill, an elongate belt runway directed transverse to roll axis 60 of said mill, a tension device applicable to draw out a belt being rolled, along said runway, and a power driven rotary-shear mounted for progression across said belt in the plane thereof, and retraction thereafter from the space occupied by 65 said belt, by the power driving means.

JAMES L. ADAMS, JR.
